RECORD-KEEPING CABINET

Charles L. Metzler, Alpine, N.J., and Henry A. Holzwarth, Bayside, N.Y., assignors to Visirecord Inc., Long Island City, N.Y., a corporation of New York

Filed Oct. 18, 1965, Ser. No. 87,550

Term of patent 14 years

(Cl. D33—19)

FIG. 1

FIG. 1 is a front perspective view of the record-keeping cabinet,

FIG. 2 is a side perspective view thereof, and

FIG. 3 is a side elevational view thereof.

The side of the cabinet not shown is like the side shown. Characteristic features of this design reside in combination on the cabinet disclosed having generally vertical members which intersect the planes of the generally vertical sides thereof and extend downwardly as support members, being connected at their lower ends by horizontal base members, said generally vertical members being canted inwardly, all as shown.

We claim:

The ornamental design for a record-keeping cabinet, as shown and described.
